[57] CLAIM

The ornamental design for a wall mounted clothes hanger, substantially as shown and described.

DESCRIPTION

FIG. 1 is a perspective view of a wall mounted clothes hanger showing our new design;

FIG. 2 is a perspective view in open clothes supporting position;

FIG. 3 is a top plan of FIG. 1;

FIG. 4 is a side elevational view taken from the left of FIG. 2;

FIG. 5 is a fragmentary bottom plan view of FIG. 2; and

FIG. 6 is a front elevational view of FIG. 2.
The rear is flat and unornamental.
